UNITED STATES PATENT OFFICE

144,159

DESIGN FOR A MOTH PREVENTIVE TABLET

Donald Deskey, Annandale, N. J., assignor to
Koppers Company, Inc., Pittsburgh, Pa., a cor-
poration of Delaware

Application June 5, 1945, Serial No. 119,919

Term of patent 14 years

(Cl. D16—3)

To all whom it may concern:

Be it known that I, Donald Deskey, a citizen
of the United States, residing at Annandale,
county of Hunterdon, and State of New Jersey,
have invented a new, original, and ornamental
Design for a Moth Preventive Tablet, of which
the following is a specification, reference being
had to the accompanying drawing, forming a part
thereof:

Figure 1 is a face view of a moth preventive
tablet embodying my new design;

Figure 2 is a view taken from the left or right
of Figure 1, both sides being the same; and

Figure 3 is a view taken from the top of Fig-
ure 1.

I claim:

The ornamental design for a moth preventive
tablet, substantially as shown and described.

DONALD DESKEY.
